UNITED STATES PATENT OFFICE.

WALTER HAHNEMANN, OF KITZEBERG, KIEL, GERMANY, ASSIGNOR TO THE FIRM
SIGNAL GESELLSCHAFT M. B. H., OF KIEL, GERMANY.

ANTENNA STRUCTURE ON AEROPLANES FOR WIRELESS SIGNALING.

1,219,550.

Specification of Letters Patent. Patented Mar. 20, 1917.

Application filed January 13, 1915. Serial No. 2,018.

To all whom it may concern:

Be it known that I, WALTER HAHNEMANN, a subject of the Emperor of Germany, residing at Kitzberg, Kiel, Germany, and whose post-office address is in care of Signal Gesellschaft m. b. H., Kiel, Werk Ravensberg, Germany, have invented certain new and useful Improvements in Antenna Structures on Aeroplanes for 10 Wireless Signaling; and I do hereby declare the following to be a full, clear, and exact description of the invention, such as will enable others skilled in the art to which it appertains to make and use the same.

15 In Letters Patent of the United States No. 1,116,059, issued to me on November 3rd, 1914, I have described an antenna structure combined with an aeroplane wherein one conducting element is consolidated with the aeroplane structure and the second conducting element is formed by wires extending from the top of a single self-supported mast to insulated members attached also to connections fastened to extremities of 25 the aeroplane. This mast rises above substantially the center of gravity of the aeroplane, and preferably is made of insulated material such as bamboo, and is fastened to the rigid parts of the aeroplane structure. 30 In order to keep the effective portions of the antenna away from the conducting parts of the aeroplane structure, the length of the said second conducting element is materially limited, and for that reason the 35 range and effectiveness of transmission is limited.

The object of the present invention is to increase the range over which wireless waves may be transmitted from and received by an operator on the aeroplane, and also to increase the effectiveness of the transmission, whether the aeroplane is in flight or on the ground. I do this in the present invention by providing a plurality 40 of masts carrying the second conducting element between their tops and being arranged symmetrically of the longitudinal axis of the aeroplane in such wise that the stability and maneuvering properties of the aeroplane are not interfered with, whether the aeroplane is of the monoplane, biplane or polyplane type. In some cases it suffices 45 to provide two masts rising from the supporting planes symmetrically of the longi-

tudinal axis of the aeroplane, but in other cases I prefer to add a third mast rising from the tail supporting structure considerably removed from the supporting planes. The wires between the tops of each pair of the masts are preferably arranged according 50 to the flat top type of antenna, and I may also provide, if desired, one or more wires extending from the top of one or more of the masts to the aeroplane, with insulating members inserted to provide effective elevated portions thereof. In all cases the masts may be shorter than in the case of the single mast of the patent above referred to, because the part of the antenna extending between the tops of the mast is more 55 advantageously located with respect to the conducting parts of the aeroplane. This condition gives greater latitude in design for any desired degree of stability in flight and maneuvering capabilities in launching 60 and landing, while at the same time the range of transmission of the wireless apparatus is still greater than obtains with the single mast structure. The height of the masts is less than the height of a mast for 65 the same range in one-masted aeroplanes, as before stated, the height of which may not, for the purposes of obtaining a sufficient range, be less than one-half of the length of the wings, and may not, for purposes of safety, be greater than the length 70 of the wings.

In the accompanying perspective drawings illustrating several embodiments with 75 my invention in application to a biplane, 90 as an example,

Figure 1 shows two masts and a flat top antenna;

Fig. 2 shows three masts with a triangle of flat top antenna forming the second conducting element of the system; and

Fig. 3 shows an arrangement like Fig. 2 with the addition of conducting elements fastened between the tops of the masts and the aeroplane.

In all the embodiments the supporting planes *p*, the tail supporting structure *f*, and the launching and landing gear *l* are of the well known kind. The steel tubes *b* and *b'* extend a little above the top of the upper 105 supporting plane at substantially equal distances on the two sides of the longitudinal center line of the aeroplane. These masts

are fastened rigidly to the aeroplane structure in any suitable way and are guyed by the wires c and c' . The masts a and a' are preferably of bamboo and are fastened in 5 the steel tubes b and b' , rising therefrom in a substantially vertical direction to a suitable elevation above the top supporting plane.

In Fig. 1, a single flat top antenna, made 10 up of two parallel wires in a substantially horizontal plane, forms the second conducting element and is connected by the wire c to receiving or transmitting apparatus of the well known kind, located in convenient 15 relation to the operator's seat.

In Fig. 2 a third mast a^2 , similar to the others, rises in a substantially vertical direction from the steel tube b^2 , which is rigidly fastened and guyed by the wires c^2 20 to the tail supporting structure at a point considerably removed from the supporting planes. The conducting parts, d , d' and d^2 of the antenna are arranged triangularly between the tops of the three masts.

Fig. 3 shows the three flat top elements, d , d' and d^2 connected to the receiving or transmitting apparatus by wires e , e' and e^2 , as in Fig. 2, and it also shows the wires g , g' and g^2 extending from the tops of the 30 masts to the aeroplane, the effective portions of these wires lying between the tops of the masts and the upper insulating members i inserted therein.

In all of the embodiments, the frame of 35 the aeroplane is made up of conducting elements and is used as one element of the antenna structure. Furthermore, the masts, whether two in number or three, are symmetrically disposed relatively to the longitudinal axis of the aeroplane.

Having thus described my invention, what I claim is:

1. The combination with an aeroplane, of 45 an antenna structure for transmitting or receiving wireless signals, comprising two masts rising from the supporting planes symmetrically of the longitudinal axis of the aeroplane, a conducting element extending between the tops of the masts in a plane substantially parallel with the aeroplane structure and being insulated therefrom, and another conducting element consolidated with the aeroplane structure and extending substantially the distance between the masts.

2. The combination with an aeroplane, of 55 an antenna structure for transmitting or receiving wireless signals, comprising two masts rising from the supporting planes symmetrically of the longitudinal axis of the aeroplane, a third mast rising from the tail supporting structure, considerably removed from the supporting planes, a conducting element extending between the tops of the masts in a plane substantially parallel with 65 the aeroplane structure and being insulated

therefrom, and another conducting element consolidated with the aeroplane structure and extending substantially the distance between the masts.

3. The combination with an aeroplane, of 70 an antenna structure for transmitting or receiving wireless signals, comprising an electrically conducting element consolidated with the aeroplane structure, a plurality of masts extending above the aeroplane structure symmetrically of the longitudinal axis thereof and being insulated therefrom, and a second conducting element extending between the tops of the masts and also from the tops of the masts to insulating members 80 in connecting parts fastened to the aeroplane structure.

4. The combination with an aeroplane, of 85 an antenna structure for transmitting or receiving wireless signals, comprising an electrically conducting element consolidated with the aeroplane structure, a plurality of masts extending above the aeroplane structure at points removed from the center of gravity thereof, and being insulated therefrom, and a second conducting element extending between the tops of the masts, the height of each of the masts being less than the height of a mast for the same range on a one-mast aeroplane.

5. The combination with an aeroplane, of 95 an antenna structure for transmitting or receiving wireless signals, comprising an electrically conducting element consolidated with the aeroplane structure, a plurality of masts extending above the aeroplane structure symmetrically of the longitudinal axis thereof and being insulated therefrom, and a second conducting element extending between the tops of the masts, the height of 100 each of the masts being less than the height of a mast for the same range on a one-mast aeroplane.

6. The combination with an aeroplane, of 110 an antenna structure for transmitting or receiving wireless signals, comprising an electrically conducting element consolidated with the aeroplane structure, two masts rising from the supporting planes symmetrically of the longitudinal axis of the aeroplane, and a second conducting element extending between the tops of the masts and being insulated from the first conducting element, the height of each of the masts being less than the height of a mast for the same range on a one-mast aeroplane.

7. The combination with an aeroplane, of 115 an antenna structure for transmitting or receiving wireless signals, comprising an electrically conducting element consolidated with the aeroplane structure, two masts rising from the supporting planes symmetrically of the longitudinal axis of the aeroplane, a third mast rising from the tail supporting structure, considerably removed 120

130

from the supporting planes, and a second conducting element extending between the tops of the three masts and being insulated from the first conducting element, the height of each of the masts being less than the height of a mast for the same range on a one-mast aeroplane.

In testimony whereof I affix my signature, in presence of two witnesses.

WALTER HAHNEMANN.
